FLUID PRESSURE OPERATED BLOWER FOR
CLEANING THE TUBES OF STEAM GEN-
ERATORS AND THE LIKE

Richard Ivor Moses, Stockton-on-Tees, England

Application December 27, 1932, Serial No. 648,922
In Great Britain December 30, 1931

2 Claims. (Cl. 122—392)

My invention relates to fluid pressure operated blowers for cleaning the tubes of steam generators and the like, and has for its principal object to provide means whereby the tubular members of the blower may be kept cool when the device is inoperative as a blower.

A further object of the invention is to provide a blower of strong and robust construction, and one which is highly economical in use, and further wherein the operative parts are adapted to be resiliently supported from the generator setting or other part.

The present invention consists in a fluid pressure operated blower for cleaning the tubes of steam generators and the like comprising a casing adapted to be secured to the wall of the steam generator, two tubular members one of which passes through and extends from said casing into the steam generator, the second tubular member also fitting into the casing being external of the first and in fixed relation thereto to define an annular space therebetween, a plurality of nozzles communicating with the interior of the first tubular member, a plurality of apertures in the wall of the second tubular member, said nozzles passing through said apertures, the first tubular member being adapted to supply pressure medium only to said nozzles, diaphragms interposed between the outer tubular member and the inner tubular member to divide the said annular space into two longitudinal passages, packing means in said casing for the ends of both tubular members, a chest in said casing for the pressure medium, an inlet for the pressure medium to said chest, two outlets for the pressure medium from said chest, one of which is in communication with the inner tubular member, and the other with one passage in the space between the tubular members, means common to both outlets for selectively admitting pressure medium either to the inner tubular member or to one passage formed by the division of the annular space, an outlet in said casing, said outlet communicating with the second passage in the space between said tubular members whereby the pressure medium may flow continuously from the inlet to the outlet through said passages when admitted thereto by said admitting means, and means for rotating said tubular members in unison.

Other features of the invention will be apparent from the following description.

In order that my invention may be more clearly understood and readily carried into prac-

tice, a preferred form will now be described with reference to the accompanying drawing, wherein:

Fig. 1 is a side elevation partly sectional of a soot blower constructed according to my invention;

Fig. 2 is a section on the line II—II of Figure 1 looking in the direction of the arrows;

Fig. 3 is a sectional plan taken on the line III—III of Figure 1;

Figs. 4 to 7 are transverse sections of details. Like reference numerals indicate corresponding parts in all the figures.

Referring to the drawing, the apparatus comprises a central conduit 1, preferably formed of weldless steel tubing, the said conduit being concentrically disposed within an outer tubular member 2. These tubular members are adapted for rotary movement within a frame casting 3, resiliently supported within a wall box 4 provided in the boiler seating 5.

The outer end of the central tube 1, is closed by a screwed and welded plug 6. The opposite ends of both the central conduit 1 and the outer tubular member 2 are closed by a second plug 8, the smaller diameter of which is screwed to engage the corresponding end of the central conduit 1. This plug 8 is further secured by means of pins 9 and may be welded at 10 for greater security.

The conduit 1 is formed or provided with two webs 12 and 13, (see Figs. 1 to 4) extending substantially the whole length of the member 2, being stopped off however, at 14 near the forward end of the blower to define two passages 16 and 17 between the tubular members 1 and 2. Both the webs 12 and 13, are preferably welded to the conduit 1. The outer end of the passage 16 is closed by the semi-annular plug 20. The web 13 is enlarged at intervals of its length to define bosses 22 each of which is bored at 23, and with corresponding borings in the inner tube and the outer tubular member 2, constitute outlet nozzles for the steam or other cleansing fluid to the boiler tubes. The borings in the tubular member 2 may be somewhat larger than that in the main bore, the annulus so formed being filled in by a welding operation.

The frame casting 3 is formed with a flange 24 adapted to receive pillar studs 25 and 26 to which are secured an extension 27, comprising a steam chest 28 with a cover 30, the said steam chest having an inlet 32 for steam or other pressure medium and ports 34 and 35 fitted with seating bushings 37 and 38, the passage of pres-

sure medium to either port being controlled by a valve 40 carried on a pin 41 and operated by the rotation of a spindle 42 carrying a bossed plate 43. The spindle is maintained steam-tight by a 5 stuffing box 44 formed in the steam chest cover 30. The part 27 is provided with an outlet 46 for the pressure fluid, this outlet being conveniently connected to a point beyond the superheater where such is used. The passage 34 admitting cleaning fluid to the central tube 1, 10 communicates with an apertured lantern member 47 in communication with apertures 48 formed in the wall of the tube 1. The lantern member 47 is positioned between packing rings 49, one of 15 which is seated on a washer 50, the opposite face of the other packing seating on the annular end of a gland 51, the whole acting as a stuffing box for the outer end of the central conduit 1. Adjustment of the parts can be effected by means of 20 the adjusting screw 52. The outer end of the tubular member 2 is similarly provided with packings 54 disposed on each side of a lantern member 55 directly communicating with an aperture 57 in the outer tube 2. The combined packings 25 are disposed between a packing washer 55 and the annular edge of the adjustable gland 60. The parts for effecting the rotation of the 30 blower tube comprise a pulley 62 mounted for rotation on the bushed stud 26 the boss of the pulley being elongated to form the boss of a pinion 63 adapted to mesh with a gear wheel 64, rigidly secured to the outer tubular member 2, whereby the rotation of the pulley 62 in either 35 direction will give the necessary rotary movement to the central conduit 1, the outer tubular member 2, and the nozzles 23 from which steam or other cleaning medium is emitted to the boiler tubes. A ball bearing 64^a is positioned between the gear wheel 64 and the flange 24 of the frame 40 3 to facilitate this rotary movement.

The combined castings 3 and 27 carrying the central and outer tubes 1 and 2 are resiliently supported within the wall box 4, rigidly mounted within the boiler seating 5 by means of studs 67, 45 the supporting means comprising the flange 66 of the wall box 4. The upper part of the flange 66 is provided with shrouded lugs 68, the lower wall of each of which is bored to slidably receive a stud 69, the lower ends of which is screwed into a boss 70 formed on the flange 24 of the frame casting 3. The upper part of each stud 69 is reduced in diameter and screwed to take a nut and washer 71' and 72 respectively, between which and the base of the cup a helical spring 73 is disposed, whereby the wall box acts as to resiliently support the blower. The lower part of the flange 66 of the wall box 4 is bored to receive a stud 75 and the flange 66 of the frame 3 is provided with a slot 71 to act as a guide while at the 50 same time permitting a certain amount of vertical and lateral movement of the blower. The borings in the shrouded lugs 68 and the width of the guide slot 71 are greater than the diameter of their engaging bolts and stud in order to provide a degree of lateral movement.

Figures 5 and 6 show in transverse section and on an enlarged scale a modified method of construction and assembly of the central conduit 1, tubular member 2, and their associated webs and 55 nozzles, Figure 5 showing the manner of inserting the central conduit 1 and its associated parts into the tubular member 2, while Fig. 6 shows the completed assembly.

In the modified construction the nozzles 76 are 60 positioned at suitable intervals along the length

of the central tube 1, and the tubular member 2 is correspondingly bored at 77 as shown to form a tight fit for the nozzles 76, when the nozzles are inserted in the bores.

Short thimbles 78 are welded to the opposite face of the central tube 1, and are positioned in alignment with internally screwed bores 79 in the tubular member 2. The tube 1 with its webs 12^a and 13^a, nozzles 76 and thimbles 78 is then inserted into the tubular member 2 with the nozzles 76, bores 77 and thimbles 78 and bores 79 in correct alignment. (See Fig. 5.) A screwed pin 80 is then screwed into the bores 78 and 79 by which means the central tube 1 is forced into the position shown in Figure 6, each nozzle 76 15 projecting through its corresponding bore in the outer tube 2. The webs 12^a, 13^a, and the inner ends of the nozzles 76 and thimbles 78 are shown welded to the inner tube 1, (see Fig. 5) while the outer ends of the nozzles 76 and also the screwed 20 pins 80 are welded to the tube 2. (See Fig. 6.)

In operation and assuming that the parts are in the position shown in Figure 1, steam or other pressure fluid enters the chest 28 by way of the inlet 32, and passes through the port 34, lantern 25 47 and apertures 48 to the interior of the central tube 1, and is emitted from the nozzles 23 to the tube sections to be cleaned. During this operation, a rotary movement can be imparted to both the central conduit 1, and the outer tubular 30 member 2 by rotation of the pulley 62, through pinion 65 and wheel 64 rigidly secured to the outer tubular member 2.

When the apparatus is inoperative as a blower, and it is desired to cool the tubes 1 and 2, the 35 valve 40 is traversed by means of a rotary movement of the spindle 42, to close the passage 34 and admit steam to the passage 35 which thereupon flows through the passage 17 between the two tubes and returns by way of the passage 16 40 passing out through aperture 57, lantern 55, and outlet 46.

Where steam is used as the cooling medium its temperature is raised during its passage through the tubes to any desired degree of superheat, the 45 steam admission being suitably regulated by means of the valve 40. The steam is then passed to a point beyond the superheater where such is used. Further, the steam leaving the tubes will have a higher pressure than the steam leaving the 50 superheater, as the pressure drop through the cooling chambers will be less than the normal pressure drop across the superheater, thereby ensuring its free discharge into the steam range.

By forming my improved blower in this way, I 55 provide effective means whereby the boiler or other tubes may be quickly cleaned of soot and other deposits, and further wherein the operative parts of the blower can be maintained in a relatively cool condition when the blower is not 60 in use.

I wish it to be understood that the above construction is given by way of illustration only, and that various modifications may be made therein. For example, the central tube 1 can be eccentrically disposed within the external tubular member 2, and any form of two-way valve can be substituted for that hereinbefore described for admitting steam, either to the central conduit or to the space between the central conduit and its outer 70 tubular member. Any suitable operative means may be employed to effect the rotation of the central conduit and the tubular member. In a further modification the resilient supporting means between the wall box and the support- 75

ing frame of the blower, can be dispensed with and the supporting frame rigidly secured to the flange of the wall box by bolts, nuts, studs, or the like, such modifications as these coming with-

5 in the scope of the invention and being employed as may be found necessary according to the particular type of boiler, superheater, or the like, to which the invention is to be applied.

What I claim and desire to secure by Letters

10 Patent is:—

1. A fluid pressure operated blower for cleaning the tubes of steam generators and the like comprising a casing adapted to be secured to the wall of the steam generator, two tubular members one of which passes through and extends from said casing into the steam generator, the second tubular member also fitting into the casing and being external of the first and in fixed relation thereto to define an annular space therebetween, a plurality of nozzles communicating with the interior of the first tubular member, a plurality of apertures in the wall of the second tubular member, said nozzles passing through said apertures, the first tubular member being 20 adapted to supply pressure medium only to said nozzles, diaphragms interposed between the outer tubular member and the inner tubular member to divide the said annular space into two longitudinal passages, packing means in said casing for the ends of both tubular members, a chest in said casing for the pressure medium, an inlet 25 for the pressure medium to said chest, two outlets for the pressure medium from said chest, one of which is in communication with the inner tubular member, and the other with one passage in the space between the tubular members, means 30 common to both outlets for selectively admitting pressure medium either to the inner tubular member or to one passage formed by the division of the annular space, an outlet in said casing, said outlet communicating with the second passage in the space between said tubular members whereby the pressure medium may flow continuously from the inlet to the outlet through said passages when admitted thereto by said admitting means, means for adjusting said first tubular 40 member longitudinally in said casing, and means for rotating said tubular members in unison.

uously from the inlet to the outlet through said passages when admitted thereto by said admitting means, and means for rotating said tubular members in unison.

2. A fluid pressure operated blower for cleaning the tubes of steam generators and the like comprising a casing adapted to be secured to the wall of the steam generator, two tubular members one of which passes through and extends from said casing into the steam generator, the second tubular member also fitting into the casing and being external of the first and in fixed relation thereto to define an annular space therebetween, a plurality of nozzles communicating with the interior of the first tubular member, a plurality of apertures in the wall of the second tubular member, said nozzles passing through said apertures, the first tubular member being adapted to supply pressure medium only to said nozzles, diaphragms interposed between the outer tubular member and the inner tubular member to divide the said annular space into two longitudinal passages, packing means in said casing for the ends of both tubular members, a chest in said casing for the pressure medium, an inlet 20 for the pressure medium to said chest, two outlets for the pressure medium from said chest, one of which is in communication with the inner tubular member, and the other with one passage in the space between the tubular members, means 25 common to both outlets for selectively admitting pressure medium either to the inner tubular member or to one passage formed by the division of the annular space, an outlet in said casing, said outlet communicating with the second passage in the space between said tubular members whereby the pressure medium may flow continuously from the inlet to the outlet through said passages when admitted thereto by said admitting means, means for adjusting said first tubular 30 member longitudinally in said casing, and means for rotating said tubular members in unison.

RICHARD IVOR MOSES.
